(57) **CLAIM**

The ornamental design for a combined game board with set of game pieces as shown and described.

DESCRIPTION

1. Combined game board with set of game pieces

1.1: Top, front perspective view of the combined game board with set of game pieces showing my new design in a position of use;

1.2: Top, front perspective view of the game board thereof shown separately for clarity of illustration;

1.3: Top plan view of the set of game pieces thereof shown separately for clarity of illustration;

1.4: Right elevational view of the set of game pieces thereof shown separately for clarity of illustration;

1.5: Front elevational view of the set of game pieces thereof shown separately for clarity of illustration;

1.6: Left elevational view of the set of game pieces thereof shown separately for clarity of illustration;

1.7: Bottom plan view of the set of game pieces thereof shown separately for clarity of illustration;

1.8: Top, back, left perspective view of the game board thereof shown separately for clarity of illustration;

1.9: Back elevational view of the set of game pieces thereof shown separately for clarity of illustration;

1.10: Top plan view of the game board thereof shown separately for clarity of illustration; and

1.11: Bottom plan view of the combined game board with set of game pieces.

The broken lines in the reproductions depict portions of the combined game board with set of game pieces that form no part of the claim.

1 Claim, 11 Drawing Sheets
